UNITED STATES PATENT OFFICE

SAMUEL L. STRIBLING, OF SAN ANTONIO, TEXAS.

WAVE-MOTOR.

1,051,974.

Specification of Letters Patent.

Patented Feb. 4, 1913.

Application filed May 1, 1912. Serial No. 694,355.

To all whom it may concern:

Be it known that I, SAMUEL L. STRIBLING, a citizen of the United States, residing at San Antonio, Fort Sam Houston, in the 5 county of Bexar and State of Texas, have invented new and useful Improvements in Wave-Motors, of which the following is a specification.

This invention relates to wave motors and 10 has for an object to provide a device of this character for the generation of power by the utilization of the lifting power of the waves and tides of the moving surface of a body of water.

15 Another object of the invention is to provide apparatus of this character which will be comparatively inexpensive and which will include substantially a battery of floating objects which are operated upon in such 20 turn by the waves and tides as will result in a continuous rotation of a power shaft.

In the drawing forming a part of this application, and in which like letters of reference indicate similar parts in the several 25 views:—Figure 1 is a side view of the motor showing parts in section. Fig. 2 is a top plan view of the same. Fig. 3 is a section on line 3—3 of Fig. 2. Fig. 4 is a perspective view of one of the floats.

30 With a view to securely anchoring the motor apparatus upon the beds of rivers, estuaries, lakes, seas, bays, sounds, gulfs and oceans; I provide a plurality of identically constructed piles, 1 which are arranged at required intervals relatively and provided with ballast containers or receptacles 2. These receptacles are open at their upper ends while the lower ends are closed by bottoms 3. Collars 4 upon the piles are 35 connected with the bottoms 3 of the ballast receptacles by means of suitable cables 5. A suitable ballast 6 in each container effectually spends its force to securely hold the container against the beds of rivers, estuaries, lakes, seas, bays, sounds, gulfs and oceans, as shown in Fig. 1 of the drawings 45 whereby the companion piles 1 will be securely maintained in proper positions.

Bearings 7 upon the upper ends of the 50 piles 1 are disposed in the same general plane with each other so as to revolvably support a power-transmitting shaft 8. Ratchet wheels 9 are secured to the power-

transmitting shaft to be operated through the medium of a battery of floats to be 55 hereinafter explained. Rocking levers 10 have bifurcated portions 11 whose arms 12 receive the shaft 8 therethrough whereby the levers are free for adjustments upon the shaft as to the rise and fall of the floats. 60

Dogs 13 are pivoted between the arms of each bifurcated portion 11 and under the influence of springs 14 the dogs are yieldingly held associated with the toothed surfaces of the ratchet wheels so as to effect the 65 required rotation of the shaft on the rise of the floats. The floats 15 have brackets 16 thereon whose ears 17 are pivoted as at 18 to similar ears 19 of yokes 20. These yokes are provided with intermediate ears 21 to 70 which the lower ends of the levers 10 are pivotally connected whereby the floats are adapted for substantially universal movements.

75 From the construction of the motor described it is evident that the battery of floats as arranged and described permits the shaft to revolve on the proper successive rise of each float and in this manner the shaft is kept in continuous motion. Power 80 taken from the waves and tides as described herein may be transmitted to any power machinery such as a dynamo or the like not shown. The cost of installation of the apparatus is comparatively small with a like- 85 wise cost of maintenance of the apparatus and from practice is found admirably adapted for the purpose intended.

I claim:—

1. A water motor including a battery of 95 piles adapted to be driven into the beds of rivers and other bodies of water subject to tides and waves, and provided with ballast containers adapted to be supported upon the beds of rivers and other bodies of water 95 subject to tides and waves, alining bearings carried by the piles, a driven shaft revolvably mounted in the bearings and means adapted to be actuated by the waves to revolve said shaft.

100 2. In a wave and tide motor, companion piles having alining bearings, a driven shaft journaled in the bearings, arms mounted for rocking movements on the shaft, ratchet wheels secured to the shaft, floats mounted 105 for rocking movements on the arms, and

means on the arms having driving contact with ratchet wheels so as to impart motion to the shaft on the rise of the floats.

3. A wave and tide motor comprising a battery of piles having alining bearings, a shaft journaled in the bearings and having fixed ratchet wheels thereon, arms mounted for rocking movements on the shaft and having yieldable dogs engaging the ratchet

wheels, floats, ears on the floats, yokes pivoted to the ears, and pivotal connections between the levers and the yokes. 10

In testimony whereof I affix my signature in presence of two witnesses.

SAMUEL L. STRIBLING.
